Arthur B. Jenkins,
ATTORNEY.

UNITED STATES PATENT OFFICE.

BENJAMIN N. B. MILLER, OF HARTFORD, CONNECTICUT, ASSIGNOR TO MARTIN C. HILLERY, OF HARTFORD, CONNECTICUT, has invented and devised a new and Improved Cushion-Heel, for use in shoes, boots, and other articles of foot-wear.

No. 862,091.

Specification of Letters Patent. Patented July 30, 1907.

Application filed April 19, 1907. Serial No. 369,113.

To all whom it may concern:

Be it known that I, BENJAMIN N. B. MILLER, a citizen of the United States, and a resident of Hartford, in the county of Hartford and State of Connecticut, 5 have invented a new and Improved Cushion-Heel, of which the following is a specification.

My invention relates to that class of devices employed for resiliently supporting the heel of a person, and more especially to that class of such devices as 10 are removably located within the heel of a shoe or like article of foot-wear.

The object of my invention is to provide a device of this class embodying an effective air-cushion, and one which while yielding to the application of weight in 15 one portion will expand in another portion so that an even support for the heel is maintained; and a further object of the invention is to provide a durable device of this class and one which may be readily placed in position.

20 A form of device in the use of which these objects may be attained is illustrated in the accompanying drawings, in which:

Figure 1 is a view in central section through a portion of the heel of a shoe showing my improved cushion cut 25 in lengthwise central section. Fig. 2 is a bottom view of the body part of the cushion. Fig. 3 is a top view of the body part with parts broken away to show construction. Fig. 4 is a view in cross section through the body part of the cushion.

30 In the accompanying drawings the numeral 10 denotes the body portion of the cushion which is made generally to conform to the shape of the inner portion of the heel of a shoe or like article. On the under surface of the body portion 10 ribs 11 are formed extending parallel or substantially so to the edge of the heel. In the form of device shown two such ribs are illustrated and a third rib extending lengthwise along the heel, the several ribs being located practically parallel and at equal distances apart laterally of the shoe.

40 Within these ribs air channels 12 are formed, these channels being wider at the bottom than at the top, thus providing lips 13 projecting in opposite directions from the partitions or dividing walls 14. These lips contract the channels 12 into a narrow opening or slit 45 21, this being of especial advantage in sealing the grooves, and also in the formation of the latter in molding.

Within the channels 12, and disposed at proper distances apart, and underlying the lips 13, are struts 15. 50 In the form of device shown these struts are oppositely located within the channels, but it is obvious that other forms and disposition of the struts may be employed, the object being to support the lips against the weight placed upon the cushion and prevent the upper and 55 under walls from coming in contact, which would cause the effects of the air cushion to be lessened. A con-

necting channel 16 extends across the body part at the ends of the channels 12, thus forming a communicating passage between each of the channels. A sealing layer 17, preferably of rubber, is firmly and tightly 60 secured to the surface of the body part overlying the channels 12, and thus completely sealing the channels. The cushion is less in thickness at the front than at the rear portion and a flap 18 extends beyond the connecting channel 16, this flap also gradually lessening in 65 thickness. A lining 19 may be employed as a finish for the under surface of the cushion, and a covering 70 layer 20 of leather or other suitable material may be secured to the upper surface of the cushion. The lining 19 is preferably formed of canvas or like comparatively tough and durable fabric, and the parts may be secured in any desired manner. By thus providing channels or chambers evenly disposed about the whole surface of the cushion, and connecting the sealed 75 channels or chambers means are provided whereby the heel of the wearer is evenly supported at all points irrespective of the uneven distribution of the weight. For instance, should the heel be rocked tending to raise one side from the cushion and place the whole 80 weight upon the opposite side, that side of the cushion upon which the excessive weight is applied will be compressed. The air, however, forced from this side of the cushion will exert an influence within the cushion at the opposite side of the heel to cause that side to expand and follow the heel upward, thus evenly supporting the weight of the wearer upon all parts of the cushion. 85 The struts 15, in this compression of one side of the cushion, will prevent the upper and under walls from coming in contact, thus preserving an air cushion at all times about all parts of the cushion. This special 90 construction enables the heel to be readily molded to proper shape and allows the mold to be easily removed.

What I claim as my invention and desire to secure by Letters Patent is:

1. A cushion heel including a body part having channels with oppositely disposed lips contracting a slit leading from the channel, communicating passages between all of the channels, and a sealing layer overlying said slots and completely sealing the channels. 95

2. A cushion heel including a body part, channels extending about the body part in a direction conforming practically to the outer edge thereof, communicating passages between all of said channels, lips overlying the channels and contracting the same to a narrow slit, struts projecting into the channels and underlying said lips, and a sealing layer overlying said slits and completely sealing the grooves. 100

3. A cushion including a body part having ribs on its under surface extending in a direction practically conforming to the edge of the cushion, grooves formed in said ribs, communicating passages between all of the grooves, lips overlying the grooves and contracting the same to a narrow slit, and a covering layer resting upon said lips and completely sealing said grooves. 110

4. A cushion including a body part having ribs on its under surface extending in a direction practically con-

forming to the outer edge of the cushion, grooves formed in said ribs, communicating passages between all of the grooves, lips overlying said grooves and contracting them to a narrow slit, struts projecting laterally from the grooves and underlying said lips, and an ensealing layer secured closely against said lips and completely ensealing said grooves.

5. A cushion including a body part having ribs on its under surface extending in a direction practically con-
10 forming to the edge of the cushion, grooves located in said ribs, a rib extending laterally of the cushion, a communi-

cating passage between all of said grooves and located in said laterally extending rib, a flap gradually decreasing in thickness and extending forward of the laterally extending rib, a sealing layer secured closely against the upper surface of the cushion and completely sealing said grooves, and a lining covering the entire upper surface of said cushion.
